SPARKING PLUG

Ludwig Kral, Vienna, Austria

Application February 18, 1938, Serial No. 191,323
In Austria February 25, 1937

5 Claims. (Cl. 123—169)

This invention relates to an improved sparking plug for internal combustion engines especially for motor vehicles. One object of the invention is to improve the sparking efficiency. Spark plugs have to operate under the most varied conditions, namely if the engine is cold or warm or hot. In the case of battery ignition, the ignition tension drops in accordance with the increasing number of revolutions of the engine while in 10 the event of magneto ignition the said tension increases in accordance with the increasing number of revolutions of the engine. In order to improve the effect of ignition in the case of low tensions, the sparking plugs have been provided with 15 "creeper" sparking paths, namely the end of the central electrode projects, to a greater or smaller extent, beyond the surface of the insulator in which the electrode is embedded. The spark develops along said surface and thereafter jumps 20 over the air gap which generally is smaller than in the case of the sparking plugs of known construction. It has been found that in this construction the entire sparking distance, consisting of the "creeper" sparking path and the free 25 sparking gap, can be made longer than in the construction in which a free sparking gap only is provided between the two electrodes.

It has been found that, when the tension increases, the spark has the tendency to separate 30 from the "creeper" area of the insulator surface and jump in the free space to the electrode of the mass. Now, if as usual, the electrode of the mass is disposed in the plane of the insulator surface, the raising spark is forced to jump in a curved 35 path, so that its way is increased and consequently the development of a powerful spark is detrimentally affected.

The present invention is based on the idea to provide for the spark the most favorable conditions and it consists in that the mass-electrode 40 ascends over the front face of the insulator from its plane towards the axis of the central electrode, so that the spark when it lifts itself away from the creeper sparking path may form 45 itself in the free sparking gap of different lengths.

Three modes of carrying out the present invention are illustrated by way of example on the accompanying sheet of drawings in which—

Figs. 1 and 2 show a sparking plug in part- 50 sectional elevation and in plan view respectively.

Figs. 3, 4 and 5, 6 are like views of two different constructions of sparking plugs.

In the constructions shown in Figs. 1 to 4, the central electrode 1, mounted in the insulator 2, 55 terminates quite flush with the front face of the

insulator, while in the embodiment illustrated in Figs. 5 and 6 the central electrode 1 projects slightly beyond the said front face. The mass-electrode 3 is mounted in the screw-threaded part 4 of the plug and its face or edge 5 faces the central electrode and overlaps the front face of the insulator 2. In the construction shown in Figs. 1 and 2, the face 5 of the mass-electrode 3 is quite straight, starts at least in the height of the plane E—E of the front face and, at its edge, 10 forms a small free sparking gap. The face or edge 5 of the mass-electrode extends towards the axis X—X of the central electrode and is inclined at an angle of approximately 45 degrees with respect to the plane E—E. 15

Compared with the construction shown in Figs. 1 and 2, the embodiment illustrated in Figs. 3 and 4 differs in the face or edge 5 of the mass-electrode curved in such a way, that at all of its places it is substantially equally distanced from the end 20 of the central electrode.

In the construction shown in Figs. 5 and 6, the mass-electrode 3 bridges the central electrode 1, which projects somewhat from the front face of the insulator 2. The face or edge 5 of the mass-electrode 3 is eccentrically curved with respect to the central electrode 1, so that the sparking gap 25 gradually increases from one end to the other end of the face or edge 5.

What I claim is—

1. A sparking plug, comprising in combination an insulator, a central electrode mounted in and terminating substantially flush with the front face of said insulator, and a mass-electrode arranged outside said insulator and provided with a part slopingly overlapping the front face of said insulator, said overlapping part of the mass-electrode gradually approaching towards the axis of said central electrode but distancing itself from the front face of said insulator, so that the spark 40 may form itself in the free sparking gap of different lengths. 30

2. A sparking plug, comprising in combination an insulator, a central electrode mounted in and terminating substantially flush with the front face of said insulator, and a mass-electrode arranged outside said insulator and provided with a part which faces and overlaps the front face of said insulator and is inclined in a straight line towards the axis of the central electrode, so that the spark may form itself in the free sparking gap of different lengths. 45

3. A sparking plug, comprising in combination an insulator, a central electrode mounted in and terminating substantially flush with the front 55

face of said insulator, and a mass-electrode arranged outside said insulator and provided with a part which faces and overlaps the front face of said insulator and is inclined at an angle of 45 degrees towards the axis of the central electrode, so that the spark may form itself in the free sparking gap of different lengths.

4. A sparking plug, comprising in combination an insulator, a central electrode mounted in and terminating substantially flush with the front face of said insulator, and a mass-electrode arranged outside said insulator and provided with a part which faces and overlaps the front face of said insulator and gradually distances itself in 10 a curved path towards the axis of the central electrode, the centre of said curved path being dis-

posed in the point of transection of the axis of said central electrode and of the front face of said central electrode, so that the spark may form itself in the free sparking gap of different lengths.

5. A sparking plug, comprising in combination an insulator, a central electrode mounted in and terminating substantially flush with the front face of said insulator, and a mass-electrode arranged outside said insulator and provided with an eccentrically curved path which bridges eccentrically said central electrode and said insulator at some distance therefrom, so that the spark may form itself in the free sparking gap of different lengths. 5 10
